ABSTRACT

A shaving method and a shaving cutter for use in carrying out a shaving operation, wherein the cutter and the gear to be processed are rotated in crossed axes relationship and the gear is shaved by one side tooth flank of a plurality of teeth formed on the circumference of the cutter.

FIG. 10

SHAVING METHOD AND SHAVING CUTTER

BACKGROUND OF THE INVENTION

It has heretofore been proposed to carry out a shaving operation, particularly a conventional method of shaving operation as shown in FIG. 1 wherein there are provided a cutter A having helical teeth formed with a cutting edge on each flank and a gear B to be shaved, said cutter A and gear B rotating in crossed axes relationship for a crossed axes angle of α formed at the intersecting point of the axial lines of both cutter and gear. Thus the shaving operation is carried out by rotating both the cutter and gear and by moving the gear in the axial direction to extend the shaved portion over the whole width of the teeth. This conventional method of shaving operation can be carried out only by means of both flanks of a plurality of teeth formed on the circumference of the cutter, namely, by means of both driving and trailing tooth flanks at the same time.

However, the tooth flanks shaved by the driving side tooth flank and the trailing side tooth flank are different from each other in points of shaving stock and processed accuracy and consequently the accuracy of the shaved tooth flank of the gear has usually been found non-uniform. Moreover, it must be kept in mind that a regrinding procedure of the shaving cutter is one of the most important problems in the industry. Namely, the regrinding of a shaving cutter has heretofore been carried out by grinding both flanks of each tooth one by one exactly along the involute form of the teeth formed on the circumference of the cutter, thus requiring considerable procedures for processing purposes and high processed accuracy.

This kind of regrinding process has been found rather expensive under the present circumstances.

SUMMARY OF THE INVENTION

An object of the present invention is to provide a shaving method whereby it is rendered possible to make uniform the accuracy of the flanks of the gear teeth thus shaved by this shaving method.

Another object of the invention is to provide a shaving cutter suitable for carrying out the above shaving method.

Still another object of the invention is to provide a shaving cutter which is capable of being reground easily after its use. Thus the characteristics inherent in the present invention are known such that a cutter and a gear to be processed are rotated in crossed axes relationship and the gear is shaved suitably wherein the intersecting point of the axial lines of the cutter and the gear to be processed is moved in the axial direction of the cutter, according to the direction of rotation of the cutter so that one flank of tooth flank of a plurality of teeth formed on the circumference of the cutter, namely, only the tooth flank of the driving side or trailing side is used to carry out shaving the gear and then the processed accuracy of the gear can be made uniform.

The above objects and other objects and characteristics of the invention will become apparent from the following description with reference to the accompanying drawings.

BRIEF DESCRIPTION OF THE DRAWINGS

FIG. 1 is a view showing a relationship between a shaving cutter and a gear to be processed in a shaving operation.

FIG. 2 is a side view showing a meshing relationship between a shaving cutter and a gear to be processed according to the present invention.

FIG. 3 is a view illustrative of the shaving method of the present invention, showing a moving procedure of the intersecting point of the axial lines of the cutter and the gear to be processed as shown in FIG. 2.

FIG. 4 is an enlarged view of the substantial part of another embodiment of a moving procedure of the intersecting point of the axial lines of the cutter and the gear to be processed.

FIG. 5 is a side view of another embodiment of a shaving cutter according to the present invention.

FIG. 6 is an enlarged view of the substantial part of a moving procedure of the intersecting point of the axial lines of a cutter and a gear to be processed using the shaving cutter shown in FIG. 5.

FIGS. 7 and 8 are side views showing other embodiments of a shaving cutter according to the present invention.

FIGS. 9 and 10 are photographic views of the shaving cutter shown in FIG. 2.

DETAILED DESCRIPTION OF THE INVENTION

In FIG. 2, reference numeral 1 indicates a shaving cutter consisting of two cutter pieces 2 and 3, each of which is formed with a plurality of teeth 21 and 31 on the circumference thereof, one end surface of each tooth having cutting edges 211 and 212 and 311 and 312 respectively.

In the drawing, one tooth only is shown on each cutter piece 2 and 3, while all other teeth are omitted for the sake of brevity.

The above mentioned two cutter pieces 2 and 3 have said cutting edges 211 and 311 on one side, which are adapted to confront each other and both cutter pieces 2 and 3 are combined together with the clearance t therebetween.

The above mentioned cutter 1 and the gear 4 in crossed axes relationship are rotated so that the gear 4 can be shaved suitably.

At the same time, the gear 4, while rotating with the cutter, is moved in the axial direction whereby the entire width of the gear can be shaved accordingly.

By the way, in the following description, only a tooth on each cutter piece is explained with reference to its construction and action for the sake of brief explanation, but the same principle will naturally apply as it is in a plurality of teeth formed on each cutter piece. Therefore, the following description must be understood as such concerning all teeth on each cutter piece.

When the cutter 1 and the gear 4 are caused to rotate in crossed axes relationship and the gear 4 moved in the direction of the arrow L as shown in FIG. 2, namely, when moved to the left as shown in FIG. 3, the gear can be shaved by the cutting edge 211 of the tooth 21 formed on the circumference of the cutter piece 2. When the gear 4 is moved in the direction of the arrow R, one-side tooth flank of the gear can be shaved by the

cutting edge 311 of the tooth 31 formed on the circumference of the cutter piece 3. In this shaving operation, the shave-off effect occurs near the intersecting point of the axial lines of the cutter and the gear and therefore, as shown in FIG. 3, when the axial position of the cutter 1 assumes the line C—C and that of the gear to be processed assumes the line D—D, the intersecting point of both axial lines shows the point P and then the gear can be shaved by the cutting edge 211 of the tooth 21 formed on the circumference of the cutter piece 2 passing near the above mentioned intersecting point P. At the same time, since the cutting edge 212 of the tooth flank 214 opposite to the tooth flank 213 formed with the cutting edge 211 is not positioned near the intersecting point P, no shaving effect occurs on the side of the tooth flank 214 but it merely serves to guide the rotating movement of the cutter. At this instant, as shown in FIG. 2, the gear 4 to be processed is moved in the direction of the arrow L, namely, to the left as shown in FIG. 3. When the rotation of the cutter 1 goes on in the direction of F in this instance, the tooth flank 213 having the tooth 21 formed on the circumference of the cutter with the cutting edge 211 will play a trailing part and then the shaving operation is carried out by this trailing tooth flank only.

As is readily apparent from FIG. 3, the end surface between cutting edges 212 and 211 forms an acute angle with the leading tooth flank 213 but forms an obtuse angle with the trailing tooth flank 214. Likewise, the end surface between cutting edges 311 and 312 forms an acute angle with leading flank 313 and an obtuse angle with trailing flank 314. Flanks 213 and 214 are mutually parallel, as are flanks 313 and 314.

By the way, since the cutter piece 3 is not positioned near the intersecting point P, the cutter does not shave but merely serves to guide its rotation.

According to experimental results obtained by the present inventor, there occurs some extent of shaving effect even by the cutting edges 311, 312 and 211 which are not positioned near the above mentioned intersecting point P, and the amount of such shaving effect is extremely small so that it gives no bad effect on the processed accuracy of the shaved flank of the gear.

In this way, when one-side tooth flank of the gear is to be shaved and the gear is moved to the required position in the direction of the arrow L and subsequently, when the gear 4 is moved in the direction of the arrow R, the rotation of the cutter 1 is changed to the direction of the arrow G. At the same time, the gear 4 is moved at right angles to the plane passing through the above mentioned intersecting point P of the axial lines of the cutter 1 and the gear so that the axial position of the gear 4 is moved from the line D—D to the line E—E as shown in FIG. 3 and the intersecting point between the cutter 1 and the gear 4 is moved from the point P to Q on the axial line of the cutter.

When the intersecting point of the axial lines of the cutter and the gear 4 is moved to the point Q, the remaining part of tooth flank of the gear 4, the initial part of which has already been shaved in the above mentioned first step can be shaved by the cutting edge 311 of the tooth 31 formed on the circumference of the cutter piece 3.

Since the rotation of the cutter 1 goes on in the direction of the arrow G as shown in FIG. 3, the tooth

flank formed with the cutting edge 311 assumes a trailing side so that the shaving operation can be effected by the trailing tooth flank.

Simultaneously, as the cutting edge 312 of the tooth flank 314 opposite to the tooth flank 313 formed with the cutting edge 311 on the tooth 31 of the cutter piece 3 is not positioned near the intersecting point Q, there occurs no shaving effect on the tooth flank 314 but it merely serves to guide the rotation of the cutter.

Also at this instant, since the cutter piece 2 is not positioned near the intersecting point of the axial lines, there occurs no shaving effect either but it merely serves to guide the rotation of the cutter.

The disclosure made hereinbefore refers to cases where a shaving effect occurs at the trailing side of a cutter tooth flank. When carrying out a shaving operation at a driving side of cutter tooth flank, the axial position of the gear 4 has only to be moved in such a manner that when the rotation of the cutter 1 goes on in the direction of the arrow F, the intersecting point of the axial lines of the cutter 1 and the gear 4 should come on the point Q and when the rotation of the cutter 1 goes on in the direction of the arrow G, the intersecting point should come on the point P.

As the procedure of moving the intersecting point of the axial lines of the cutter 1 and the gear 4 to the axial direction of the cutter, besides the method of moving the gear as explained with reference to FIG. 3, there is also another method of moving the cutter.

Now such method will be explained in detail with reference to FIG. 4 hereinbelow.

When the axial position of the cutter remains on the line C—C and that of the gear on the line D—D respectively, the intersecting point of the axial lines falls on the point P.

In this case, the first step consists in moving the cutter to the position shown by the full line and positioning only the cutting edge 211 and the tooth 21 on the circumference of the cutter piece 2 near the intersecting point P of the axial lines of the cutter and the gear. The second step consists in moving the cutter to the position shown by the dotted line on the axial line C—C of the cutter and positioning only the cutting edge 311 of the tooth 31 of the other cutter piece 3 near the abovementioned intersecting point P.

Consequently, when the above mentioned cutting edge 211 is positioned near the intersecting point P, the direction of rotation of the cutter is rendered downward and when the above mentioned cutting edge 311 is positioned near the intersecting point P, the direction of rotation of the cutter is rendered G and thus it is possible to carry out the shaving operation only by the tooth flank of the trailing side.

When carrying out the shaving operation by the tooth flank of the driving side of the cutter, it is sufficient to make the direction of rotation of the cutter G when the above mentioned cutting edge 211 is positioned near the intersecting point of the axial lines and to make the direction of rotation of the cutter F when the above mentioned cutting edge 311 is positioned near the intersecting point of the axial lines.

In the case of carrying out the shaving operation only by the tooth flank of the driving side of the cutter, when the above mentioned cutting edge 211 is positioned near the intersecting point P, the direction of rotation

of the cutter has only to be made G and when the above mentioned cutting edge 311 is positioned near the intersecting point P, the direction of rotation of the cutter has only to be made F.

According to the shaving method of the present invention as mentioned above, the intersecting point of the axial lines of the cutter and the gear is moved onto the axial line of the cutter, whereby the gear to be processed can be shaved by either the tooth flank of the driving side of the cutter or that of the trailing side so that the processed flank of the shaved gear can be obtained in a uniform manner.

In the shaving cutter for use as explained above, the cutter 1 consists of two cutter pieces 2 and 3 and moreover, there are provided the cutting edge 211 and 311 on each confronting end of the teeth 21 and 31 formed on the circumference of the cutter piece 2 and 3 respectively.

With this arrangement, in the case of regrinding the shaving cutter, it is sufficient to grind each end surface of the cutter pieces 2 and 3. Consequently the operation of regrinding becomes very easy to carry out and what is more, the machining steps are reduced so that regrinding cost is considerably saved, as compared with conventional regrinding techniques.

FIG. 5 shows another embodiment of a shaving cutter suitable for use in the shaving method of the present invention. Namely there are formed helical teeth 6 on the circumference of a cutter piece 5 and a series of first cutting edges 63 on a first tooth flank 61 respectively from a first end surface 65 to a point near the middle of the first flank, the remaining section 66 of the first flank being a smooth surface. A series of second cutting edges 64 is formed on an opposed second tooth flank 62 from an opposed second end surface 67 up to a point near the end of the second flank, the remaining section 68 of the second flank being a smooth surface.

An example of use of the shaving cutter will be explained with reference to FIG. 6.

As shown in FIG. 6, when the axial position of the shaving cutter assumes the line C—C and the axial position of the gear to be processed assumes the line D—D respectively, there occurs the intersecting point P of the axial lines of both cutter and gear, and the shaving operation of the gear can be carried out by the cutting edge 64 positioned near the above mentioned intersecting point.

At the same time, since the tooth flank 62 formed with the cutting edge 64 and the cutting edge on the tooth flank 61 are not positioned near the intersecting point P of the axial lines of the cutter and the gear, there occurs no shaving effect on them.

When the direction of rotation of the shaving cutter assumes the direction of F, the tooth flank formed with the cutting edge 64 becomes a trailing side so that one-side tooth flank of the gear can be shaved by the tooth flank of the trailing side only.

In this way, when one-side tooth flank of the gear is to be shaved, the direction of rotation of the shaving cutter is changed to the direction of G and simultaneously, the axial position of the gear is changed to the position of E—E, then the intersecting point of the axial lines of the cutter and the gear is changed to the point Q so that the shaving operation can be carried out

by the cutting edge 63 positioned near the intersecting point Q.

At the same time, however, the tooth flank 61 formed with the cutting edge 63 and the cutting edge 64 formed on the opposite tooth flank are not positioned near the intersecting point Q, there occurs no shaving effect at all. In this case, since the direction of rotation of the shaving cutter is G, the tooth flank 61 formed with the cutting edge 63 becomes a trailing side so that it is possible to shave the tooth flank opposite to the area shaved by the above mentioned cutting edge 64 of the gear only by the tooth flank of the trailing side.

15 In shaving cutters of the type are formed a plurality of cutting edges 63 and 64 respectively on the tooth flanks 61 and 62 of the tooth 6 so that a plurality of cutting edges are found to be positioned near the intersecting point of the axial lines of the cutter and gear, 20 thus rendering its shaving efficiency by far better than that of the shaving cutter shown in FIGS. 2 through 4.

25 FIG. 7 shows another embodiment of shaving cutter according to the present invention. It consists of two cutter pieces 7 and 8 and the tooth 71 is formed on the circumference of the cutter piece 7 on one side and the tooth 81 on the cutter piece 8 on the other side. Of the tooth flanks 711 and 712 of the tooth 71 on the cutter piece 7 on one side, the tooth flank 712 is formed with the cutting edge 713.

30 Likewise, of the tooth flanks 811 and 812 on the tooth 81 formed on the other-side cutter piece 8, the tooth flank 811 is formed with the cutting edge 813.

35 As shown in FIG. 7, the above mentioned two cutter pieces 7 and 8 show that the tooth 71 on the cutter piece 7 and the tooth 81 on the other cutter piece 8 are so constituted to form a tooth in a body and furthermore, the tooth flank 712 formed with the cutting edge 713 and the tooth flank 812 formed with the cutting edge 813 respectively are joined together so as to form 40 mutually opposite tooth flanks and then they are combined by fixing means such as bolts and nuts, whereby a shaving cutter can be obtained almost similar to that shown in FIGS. 5 and 6.

45 In shaving cutters of this kind are provided two cutter pieces 7 and 8 so that it is possible to provide cutting edges all over the entire width of the tooth only in the tooth flank of the same direction as that of the tooth 71 and 81 provided on the cutter pieces 7 and 8

50 respectively and therefore the manufacture of shaving cutters themselves is rendered easier than that shown in FIGS. 5 and 6. Moreover, since the shaving cutter consists of two cutter pieces, the tooth width of each piece may be made small and so it is rendered possible to ensure 55 least occurrence of error in the processing of cutter tooth flanks, thereby enabling a shaving cutter with a precise tooth flank to be obtained.

55 FIG. 8 shows still another embodiment of a shaving cutter according to the present invention.

60 This embodiment provides the interposition of a spacer 10 between the two cutter pieces 7 and 8 which are shown in FIG. 7 and also the formation of the clearance S therebetween. In a shaving cutter of this type, the clearance S is provided in the joint portion 65 between the two cutter pieces 7 and 8 so that the shaving cutter can deal with cut dust during the shaving operation more efficiently than those shown in FIGS. 5,

6 and 7, thus ensuring improvements in overall processed accuracy.

What is claimed is:

1. A shaving cutter comprising a plurality of teeth, each tooth having a first flank and a second flank, the second tooth flank being an opposite flank to said first tooth flank, and first and second end surfaces, the first tooth flank running from said first end surface to said second end surface and having a series of first cutting edges thereon extending from the first end surface to a point near the middle of the first flank and having a smooth surface over the rest of the first flank, the second tooth flank running from said first end surface to said second end surface and having a series of second cutting edges thereon running from the second end surface to a point near the middle of the second flank and having a smooth surface over the rest of the second flank.

5

10

15

2. A shaving cutter according to claim 1 wherein the cutter comprises two disc-like pieces, each piece having a plurality of tooth portions, the pieces being arranged near each other so that the tooth portions on one of the disc-like pieces are aligned with the tooth portions on the other of the disc-like pieces, the aligned tooth portions forming said teeth the cutting edge of the first flank of each tooth and the dull edge of the second flank of each tooth being on a first one of the disc-like pieces and the cutting edge of the second flank of each tooth and the dull edge of the first flank of each tooth being on a second one of the disc-like pieces.

3. A shaving cutter according to claim 2 wherein said two disc-like pieces are arranged near each other to leave a small clearance gap therebetween.
